UNITED STATES PATENT OFFICE

136,480

DESIGN FOR A HAND LOTION BOTTLE

James L. Younghusband, Chicago, Ill.

Application March 9, 1943, Serial No. 109,698

Term of patent 14 years

To all whom it may concern:

Be it known that I, James L. Younghusband, a citizen of the Dominion of Canada, residing at 30 West Hubbard Street, Chicago, Illinois, have invented a new, original, and ornamental Design for a Hand Lotion Bottle, of which the following is a specification, reference being had to the accompanying drawing, forming a part thereof.

Referring to the drawing, Fig. 1 is a front elevational view of a hand lotion bottle embodying my new design; Fig. 2 is a side elevational view, Fig. 3 a rear elevational view, and Fig. 4 a bottom plan view of the same. Fig. 5 is a side elevational view showing the cap removed.

I claim:

The ornamental design for a hand lotion bottle, substantially as shown.

JAMES L. YOUNGHUSBAND.
